REEL TENSION DEVICE

Gilbert J. Kennedy, Philadelphia, Pa., assignor to
Radio Corporation of America, a corporation
of Delaware

Application January 25, 1946, Serial No. 643,289

6 Claims. (Cl. 242—75)

1

This invention relates to a new and useful reel tension device which is particularly adapted to winding machines for handling extraordinary thin strip material.

This application is a continuation in part of my copending application Serial No. 536,219 filed May 18, 1944, now abandoned.

An object of this invention is to provide a spring tension reel or dereeling device to permit the winding or unwinding of extra thin strip material which previously could not be handled because the tension applied by previously known reel tension devices would cause the extra thin material to tear.

Another object of this invention is to provide a reel tension device which will greatly reduce the manufacturing cost of electrical condensers wound with alternately arranged strips of extraordinary thin metal foil and interposed insulating strip material.

A feature of this invention is the arrangement of a spring frictioned mandrel running on conical pivot bearings for supporting a reel or spool having wound thereon a roll of extra thin strip material. An adjustable strip tension means is arranged at a distance from the mandrel axis to give minute frictional adjustment to the mandrel, such that the roll of thin strip material may be wound or unreeled without any tendency to weave or tear.

This reel tension device is particularly adapted to provide improved strip tension means for winding coil or roll condensers on a winding machine, as is described in the Harold I. Danziger patent, 1,940,847. According to my invention, the metal foil rollers are positioned on the winding machine, immediately over the winding feed rollers, to control the weaving of the foil. The drag or strip tension on the foil rolls, according to my invention, is made more sensitive to control and thus, permits the winding of thinner foil than was heretofore practical in roll condenser production.

My invention also conceives the use of conical pivot bearings on a mandrel. The required pull on the foil reel (when the machine mentioned above starts winding) is thereby cut down to almost nothing as the frictional resistance of both the bearings and the spring friction is applied so as to bear as close to the center of the mandrel as is practical.

Roll condensers (which were previously wound on the above mentioned Danziger machine) generally comprise layers of paper and metal foil wound in roll form so as to have the long lengths

of paper and foil strips confined to a small space. These rolls were then impregnated in oil and wax, and placed in small sealed cans.

Prior to the adoption of the metallic foil de-reeling method of my invention, the above mentioned capacity units were of necessity wound with a comparatively heavy foil, for the reason that it was found impossible to employ metal foil which was thinner than .00025 of an inch, because when thinner foils were used, utter failure resulted due to the fact that with high speed winding necessary for high speed production methods, the thinner foil would frequently break. This breakage thus caused a larger percentage of rejections and subsequent increased cost of the condensers.

Each time the condenser foil breaks in winding a condenser, approximately 6 ft. of expensive paper and 3 ft. of expensive metallic foil is scrapped, thus adding to the production cost of the condensers. Opal wax impregnation was also necessary in order to keep the electrical capacity high and the physical volume small, in order to place the units in a small container.

By my invention, extremely thin foil can now be used in the production of condensers without any danger of breakage. For example, I have found it possible to wind capacitor units using aluminum foil or other similar material as thin as .00016 of an inch.

Because of using the thinner foil, it is possible to simplify the production of roll condensers by employing a standard inexpensive castor oil impregnation treatment.

In order to wind inexpensive roll condensers having a maximum electrical capacity and a minimum physical volume, it is necessary that the standard oil type treatment mentioned above be employed, and not an opal wax treatment which reduces the physical size of a condenser.

The standard castor oil treatment is inexpensive as compared with the opal wax method.

My invention will be understood by referring to the accompanying drawing in which:

Fig. 1 is a front elevation of a portion of the Danziger winding machine having mounted thereon two separate reel tension devices of my invention.

Fig. 2 is a side elevation of Fig. 1.

Fig. 3 is an enlarged detailed section of the reel of my invention, and

Fig. 4 is a side elevation of Fig. 3.

Referring now in detail to Figs. 1 and 2 of the drawing, the Danziger machine mentioned above as Patent No. 1,940,847 comprises a frame com-

posed of two upstanding parallel plates, a front plate 10 and a rear plate 11, spaced apart and suitably joined together by spacing members which include a motor support plate 10A. The main driving motor 12 is secured to plate 10A. Motor 12 has a pulley 14 which with a belt 15 drives a rotatable shaft 13 and a pulley 13A. The rotatable shaft 13 extends transversely through the frame at the lower portion thereof. One end of shaft 13 is split and projects forward from the front plate 10 and constitutes the winding mandrel for the condenser. The other end of the shaft 13, in addition to pulley 13A, carries a gear 16 through a train of gears (not shown) which provides the proper movement for the shaft 13. Further description as to the structural details of the gear mechanism will be found by referring to the above mentioned patent, as the train of gears does not form a part of my present invention.

For reasons of clarity, all parts added to the Danziger winding machine which describe my invention are prefixed with a numeral 2, in order not to confuse my elements with those employed in the Danziger winding machine.

The front plate 10 of the Danziger machine is shown with two pair of drums 23, 23' and 25, 25', each one of which is adapted to carry a roll of paper dielectric. Located intermediate the drums 23, 23' and 25, 25' are fixed shafts 24 and 24'; which shafts in the Danziger machine, prior to my invention, were adapted to carry a roll of metal strip normally retained on the shaft by an ordinary spool. One of the reel tension devices of this invention is located on shaft or rod 24, and the other reel tension device is located on shaft or rod 24', each being located at an angle of about 45° with respect to the vertical axis of the machine, so that the strip of foil is brought down to guide rollers 27 and 27' located in a position closely adjacent the foil cut-off knives 37. In this position, the foil rolls 221 and 227, which rolls are located so as to unwind on the dereeler device of this invention, are placed as close as possible in line with the paper strips, and thus results in keeping the weaving motion from the strip of foil as it unrolls at a minimum. The foil and paper dielectrics are brought closely together between rollers 28 and 28' and are wound into a condenser roll by rotatable shaft 13. When the two reel tension devices of this invention are employed on the Danziger machine, the foil support drums (shown as 24 and 24' only on the above mentioned patent) and their associated spring tensioned members are omitted.

The reel tension devices of this invention are substituted and mounted on shafts 24 and 24' of Fig. 1, and as mentioned above are adjusted in and out from the back of the machine by means of a threaded knurled handwheel 230 in order that the position of the foil will coincide exactly with the paper strips.

The reel tension device or dereeler 201 of this invention as shown in the drawings, comprises essentially a yoke member formed of a back plate 202 and a front plate 203. The back plate 202 has secured integral therewith a shaft bearing portion 202A which is reamed out to just clear shaft 24. The front plate 203 is provided with an integral handle portion 207. A rod 205 is secured to plate 202 by a set screw 206, and by having its ends pass through apertures in plates 10 and 201 rotation of the reel tension device is prevented. The handle portion and plate 203 have an enlarged aperture 207A, and a counter-

bored portion 207B is made sufficiently large to seat an extension spring 233, the outside diameter of the spring being substantially the same as the outside diameter of the counterbored hole so that the spring will be retained centrally on member 207 and will not bear upon shaft 24. The front plate 203 is provided with large support rod apertures so that the machine operator can, by grasping the handle portion 207 and compressing the spring 233, rotate the front plate 203 by moving it forward toward the operator and thereby freeing it from the collar support rod 208 and also the guide rod 205. Then by turning the handle 207 approximately 90° from the normal operating position, the front plate will be clear of the roll of foil 227, in which position the roll 227 may be withdrawn and a new roll of foil can be placed thereon. A set screw 202B retains collar support rod 208 in position after adjustment. A sloping collar 209 is secured to rod 208 by a set screw 210. The maximum width of collar 209 is located at the lower portion 211 and serves as a fulcrum point. A metal backing plate 227A keeps the spool of foil 227 in proper alignment. The hub portion 221 is secured in its operating position on mandrel 220 by means of a set screw 224. The lower end of the front and back plates are each provided with a mandrel bearing support, as is shown in detail by Figs. 3 and 4. The front plate 203 is shown as having a small aperture 212 to retain a hardened steel conical pointed mandrel bearing center member 214. The back plate 202 has a larger aperture 213 which supports a cylindrical housing member 215. The forward part of the housing member is provided with a flange portion 216, and the rear portion has a smaller aperture in which there is provided a hardened steel mandrel conical bearing member 217. Intermediate the flange 216 and the conical bearing member 217, the housing member 215 has an oil hole 218 for lubricating the mandrel and bearing 217. A set screw 219 is located near flange 216, and is arranged with sufficient length to engage in a circular groove or annular slotted portion 220A in the mandrel 220, thereby preventing the mandrel from coming off from its bearing in the back plate 202 when the operator changes the foil rolls. The mandrel 220 is drilled and countersunk at each end thereof for turning on the ground conical center members 214 and 217. The reel 221 is provided with a hub portion 221A which retains a roll of foil 227. The reel 221 also includes a flange roll backing portion 222 and a keyway 223. A flat steel spring 226 is located within the keyway 223. The spring 226 is secured to reel 221 by a roundhead machine screw 225. The purpose of spring 226 is to engage the inner cardboard wall of a spool, to retain the roll of thin aluminum foil 227 in a fixed position on the hub portion 221A. The forward end of shaft 24 is threaded at 231 with an adjustable threaded nut 232. Light friction is applied to the mandrel 220 by means of compressing the spring 233 which is placed around shaft 24 and arranged to bear only against member 207. The reel mandrel 220 rotates on the two hardened steel conical pivoted points 214 and 217, as is shown in Fig. 3. As before mentioned, the collar 209 which is located on a rod 208 is chamfered away slightly to provide a fulcrum point 211. Very light pressure is exerted on the pivoted points by the spring 233 using point 211 on collar 209 as the fulcrum point. The fulcrum point bears against the inside surface of plate 203. The spring tension device of this invention, as

mounted on shaft 24, is constrained from moving inward by a collar 240 which is secured to shaft 24 by a pin 241. A collar 240A locates member 202A in its proper forward position on shaft 24, and the collar is retained by a set screw 241A. A slight clearance is maintained between the spacing shaft 208 and the aperture in the plate 203, to prevent cramping or binding. Adjustment of the spring tension device, with respect to the front plate 10 of the Danziger machine, is made by the rotation of the threaded nut 232. This adjustment is required in order that the metal foil strips will unwind in proper alignment with the feed rollers 28 and 28'. The guide rod 205 is secured to the rear plate 202 by a set screw 206. One end of guide rod 205 extends through a large aperture in plate 10 in front plate 203 and positions the reel tension device on plate 10. The accurate setting of the collar 209 is accomplished by the tightening of set screw 210 when the proper distance is determined (where the conical pivoted bearing 214 enters mandrel 220) for providing the proper friction on the mandrel by the adjustment of the tension of spring 233.

In the operation of the two reel tension devices of this invention, one device is placed in proper alignment on rod 24, and the other reel tension device is placed on rod 24'. The tension devices of this invention are placed in such a position on rods 24 and 24' that the lower or pivot ends of the two mandrels face each other and are set at a proper angle, preferably about 45° with respect to a line located in the center of the machine just above the feed rollers 28 and 28'. In this position, the spools of metal foil 221 and 221' are located so as to be in line with one side of each one of the guide posts 27 and 27'. The foil strips are fed down to the winding mandrel 13 through the feed rollers 28 and 28', together with the paper strips arranged in their proper position with respect to the foils as shown in Fig. 1 of the drawing. In preparing the capacitors for winding, the operator adjusts the proper foil tension on the mandrel 220 by applying friction on bearings 216 and 217 through the operation of turning the adjusting member 232 to compress spring 233. Adjustment of the fulcrum point 211 may also be made at this time. The paper and foil strips are next fed, through the feed rollers 28 and 28', to mandrel 13 which rotates until the desired number of turns are obtained. The foil strips are then cut off by the cut-off knives 37, as is customary with the usual method of winding condensers, and then the paper strips are cut off in the usual manner. The condenser is then removed from the machine, and a sticker is attached to the roll to prevent its unrolling. The foils and paper are then again brought down through the feed rollers to the winding mandrel 13, and the cycle of operation is repeated.

The reel tension device of this invention has proven to be very efficient for producing capacitors of extraordinary thin foil, and thus greatly reduced the cost of manufacture (for example by omitting the expensive wax process, by using less weight of metallic foil, by releasing other machines for production, and by an improved capacitor unit having a maximum capacity for a minimum volume).

It should be understood that this invention should not be limited to the winding of a particular type of capacitor mentioned in the specification but may be used to apply proper winding tension to any other thin strip or metal foil material.

What is claimed is:

1. A reel tension device for unwinding thin strip material from a reel comprising a pair of parallel spaced reel support members, a pivoted bearing located in each one of said support members at one end thereof, a reel for retaining a spool of thin strip material, a mandrel for said reel secured for rotation between said pivoted bearings, a member for spacing said parallel plates apart and to support said reel therebetween, said spacing member being located in apertures at the other end of each one of said support members, a support rod secured to a position intermediate the ends of said parallel support members, and a spring member secured to said support rod for applying friction between the pivoted bearings and said mandrel whereby a slight unwinding tension is maintained on the thin strip material.
2. A reel tension device for unwinding thin strip material from a reel comprising a pair of parallel spaced reel support members, a pivoted bearing located in each one of said support members at one end thereof, a reel for retaining a spool of thin strip material, a mandrel for said reel secured for rotation between said pivoted bearings, an adjustable spacing member for spacing said parallel plates apart and to support said reel therebetween, said adjustable spacing member being located in apertures at the other end of each one of said support members, a support rod secured to a position intermediate the ends of said parallel support members, and an adjustable compression spring member secured to said support rod for applying friction between the pivoted bearings and said mandrel whereby a slight unwinding tension is maintained on the thin strip material.
3. A reel tensioned device for retaining a reel of thin strip material comprising a yoke member, an adjustable spacing member located at one end of said yoke member, a rotatable reel located within said yoke member and positioned at an end opposite from said adjustable spacing member, a collar having sloping sides secured to said adjustable spacing member and forming a fulcrum point on said yoke member, a rotatable mandrel for said reel, and a spring member secured to said yoke member for applying friction on said mandrel whereby a slight tension is maintained on the thin strip material when it is unwound.
4. The combination of a condenser winding machine of the type having a plate with shafts for supporting a plurality of spools, and a rotatable winding mandrel for winding a condenser from dielectric and thin metal strips located on said spools, a pair of reel tension devices for retaining the spools of thin metal strip, each one of said devices having a first reel support member which is adjustably secured to one of the shafts on said plate of the condenser winding machine, a second reel support member spaced from said first mentioned reel support member, an adjustable spacing member for spacing said first and second reel support members, a support rod for adjustably retaining said reel tension devices in an operative position, a reel for retaining a spool of thin metal strip, a mandrel for said reel secured for rotation between said first and second reel support members, and a spring compression member adjustably secured on said support rod for applying friction to said last mentioned mandrel, whereby a slight unwinding tension is maintained on the thin metal strip.
5. The combination of a condenser winding

machine of the type having a plate with shafts for supporting a plurality of spools, and a rotatable winding mandrel for winding a condenser from dielectric and thin metal strips located on said spools, a pair of reel tension devices for retaining the spools of thin metal strips, each one of said devices having a first reel support member which is adjustably secured to one of the shafts on said plate of said condenser winding machine, a second reel support member spaced from said first mentioned reel support and arranged to be removable therefrom, an adjustable spacing member for spacing said first and second reel support members, a support rod for adjustably retaining said reel tension devices in an operative position, a reel for retaining a spool of thin metal strip, a mandrel for said reel secured for rotation between said first and second reel support members, and a helical spring compression member adjustably secured on said support rod for applying friction to said last mentioned mandrel, whereby a slight unwinding tension is maintained on said thin metal strip.

6. The combination of a condenser winding machine of the type having a plate with shafts for supporting a plurality of spools, and a rotatable winding mandrel for winding a condenser from dielectric and thin metal strips located on said spools, a pair of reel tension devices for retaining the spools of thin metal strip, each one of said devices having a first reel support member which

is adjustably secured to one of the shafts on said plate of said condenser winding machine, a second reel support member spaced from said first mentioned reel support member and arranged to be removable therefrom, an adjustable spacing member for spacing said first and second reel support members, a support rod for adjustably retaining said reel tension device in an operative position, a reel for retaining a spool of strip material, a rotatable reel mandrel having an annular slotted portion for its retention on said first mentioned reel support member, to permit the replacement of a spool of thin strip material, and a spring compression member adjustably secured to said support rod for applying friction to said last mentioned mandrel, whereby a slight unwinding tension is maintained on said thin strip material.
